Frank Scott Crowhurst

Munn & Co.

ATTORNEY

UNITED STATES PATENT OFFICE

FRANK SCOTT CROWHURST, OF LOS ANGELES, CALIFORNIA

BUILDING CONSTRUCTION

Application filed April 9, 1928. Serial No. 268,704.

My invention relates to building construction, and more particularly to furring strips, and is referred to herein as an improvement upon the form of my invention shown and described in my co-pending application for U. S. Letters Patent for Building construction, Serial No. 257,366, filed February 27, 1928.

My invention is essentially directed to a new, novel and useful furring strip, and means for attaching the same to the studding of a building so that there is existent at each stud a flexible connection or support for the furring strip, which said connection is positively self-acting and free to function where it will adapt itself to relative movements between the studs and a plastic wall surface of which the furring strip is an incidental or co-acting element of said wall surface, thereby insuring the strength of the wall and preventing cracking thereof during settling periods or by virtue of climatic changes.

A further object of my invention is to provide novel positively-functioning means for attaching the furring material to the studding, which said means can be quickly driven into the individual studs as the furring material is held in position.

Another important object of the invention in conjunction with my improved furring strip is a co-acting connecting device or fastening which can be applied to the stud by an unskilled person.

A still further object of the invention is to provide an attaching device for the furring which can be driven into position by one standing in front of the material and without any necessity of any guess-work as to its point of application to the studding.

In the accompanying drawing,

Figure 1 is a view in horizontal section through a portion of a wall construction showing the furring strip attached to the studs;

Figure 2 is a similar view on an exaggerated or enlarged scale of a portion of the furring strip attached to a stud;

Figure 3 is a view in front elevation of a portion of the furring strip;

Figure 4 is a section on line 4—4 of Figure 2;

Figure 5 is a perspective view of the fastening or attaching device;

Figure 6 is a view similar to Figure 5 of a further form of attaching device; and

Figure 7 is a view similar to Figure 6 of a still further form of fastening device.

On reference to Figure 3, it is observed that the furring strip is of the type made up of equidistantly spaced-apart horizontal wires 10 and vertical equidistantly spaced-apart wires 11, the association of the latter with the former being such that fabric is provided with relatively large rectangular interstices 12. The horizontal wires 10 are all formed with inwardly offset U branches 13, the same including a long lead 14 disposed in parallelism with the body or front face of the lathing strip, and connecting end portions 15, 15, it being preferred that the said end portions extend at right angles to the front face of the furring strip. In practice, it is found suitable for my purpose that the portions 15 possess a length of about five-sixteenths of an inch and that the length of the lead 14 be approximately three inches. This allows ample clearance between an applied wall surface which I will subsequently refer to and the studs that will prevent any rough plaster from in any way interfering with the action of my invention when applied.

In Figure 1 it is observed that the U-shaped portions 13 are arranged in spaced-apart vertical rows so that one row will co-incide with a respective stud with which it is associated and wherein the leads 14 traverse in horizontal directions the front face of the stud. In order that my improved furring strip, when applied to the studs A, Figures 1 and 2, may be free to compensate itself for any relative movement set up in the studs or any stresses transferred thereto through usual causes, I provide a fastening or connector 16, the same being staple-like and provided with legs 17, 17, adapted to straddle the lead 14 and to be driven into the stud, and as illustrated these legs are joined together by a loop 18 which, when the legs 17 are fully applied, receives the lead 14 in embracing relation.

tionship thereto but with clearance between the walls of the loop and the exterior annular surface of said lead, as shown in Figure 4. In this manner, it manifestly follows that the connection between the stud and the furring strip is flexible and that there is provision made for movements between the furring and its studs for satisfying movements in all directions, preferably movements in a horizontal direction.

In Figure 2, I have illustrated a wall surface B applied in the customary manner to its lath C, the latter connected at D in any suitable well-known manner with the furring material. I have now suspended the wall surface so that it will positively accommodate itself to any movements in the frame of the building so as to avoid the formation of cracks in the surface and to adequately insure the surface against undue damage.

In Figure 6 the fastening 19 has a shank 20 adapted to be driven into a stud and the said shank may be of a flexible wire type wherein it may be bent over at 21 to form a loop for the reception of the aforesigned lead 14 of the furring strip, the short terminal 22 of the loop preferably formed with a flat head 23 adapted to come against an adjacent surface of the stud when the fastening is fully applied. The loop is proportioned so as to give clearance between its walls and the annular surface of the lead 14 from one end of the latter to the other, as is also the case in the preferred embodiment of my invention.

Figure 7 shows a still modified form of fastening consisting of a pointed shank 24 adapted to be driven into a stud and at one end the shank is formed with a driving head 25 which, when struck with a hammer or other suitable tool, will cause the point of the fastening to find proper purchase with its joist. As an integral part of the head 25, I have shown a branch arm 26 which terminates in a supplemental spur 27 of short length as compared with the length of the shank 24. This is adapted to be driven slightly into the joist and to stop when the shoulder 28 thereof reaches the stud. In this way, the space under the head 25 functions as a loop and there is a permanent clearance between all surfaces of the loop thus formed and the coacting lead 24 of the furring strip which passes through the loop.

I do not wish to be limited to any particular form of fastening when carrying the invention into practice, as I am primarily concerned with the form of furring in association with any suitable well-known means that will afford a way of setting up freedom of action between the studs and the furring strip when the latter is applied, all in order that the aforementioned relative movements between these parts may be positively accommodated without in any way affecting an applied plastic wall surface.

I claim as my invention:

1. Furring material having portions offset from the plane of the body of the material and adapted to come against the studs of a building frame, and means for loosely attaching the material to the studs at the said offset portions, thereby permitting the studs and the material to move relatively when the furring material is incorporated with a plastic wall surface.

2. Furring material having interstices defined partly by straight portions of the material, and means adapted to be attached to the studs of a building frame and having loops to freely receive said straight portions and to permit of a relative lateral movement of the portions with respect to the loops when the material is attached to the studs.

3. Furring material having interstices defined partly by straight portions of the material, and means adapted to be attached to the studs of a building frame and having loops to freely receive said straight portions and to permit of a relative movement of the portions with respect to the loops when the material is attached to the studs, the said straight portions being offset in one direction away from the plane of the body of the material.

4. In building construction, frame studs; a plastic wall surface; furring to which said wall surface is secured; and loop means secured to the studs and loosely connecting the furring to the studs to permit movement of the studs relative to the wall surface.

5. In building construction, means for establishing a flexible connection between furring material and the studs of a building frame, comprising furring material having portions traversing the studs and spaced apart from the body of the material, and pointed devices connected with the studs and having loops freely receiving said traversing portions for movements therein.

6. Furring means comprising a length of bendable material bent at intervals to provide spaced apart pairs of laterally projecting branches and a portion connecting each pair of branches, disposed parallel to and offset from the plane of the strip, and an attaching device having a head loosely receiving the connecting portion of the strip, and a shank capable of being driven into a stud or joist to secure the strip thereto yet permit limited movement of the stud relative to the strip when plaster is applied to the latter.

7. Wall construction comprising studding, furring having laterally offset portions, plaster carrying lathing secured to the furring, and a loose connection between the studding and furring co-acting with the offset portions of the latter to support the furring from the studding with the plaster spaced from the latter, while permitting relative

movement between the studding and furring to prevent fracture of the plaster.

8. Wall construction comprising studding; furring; plaster carrying lathing secured to the furring with the plaster spaced from the latter; and a loose connection between the studding and furring coacting with the latter to support the furring from the studding and enabling the studding to move relative to the furring to prevent fracture of the plaster.
